UNITED STATES PATENT OFFICE.

ROBERT MIEHLE, OF CHICAGO, ILLINOIS.

DEVICE FOR GIVING POSITIVE MOTION TO SLIDERS OF PRINTING-PRESSES.

SPECIFICATION forming part of Letters Patent No. 330,040, dated November 10, 1885.

Application filed March 7, 1885. Serial No. 158,091. (No model.)

To all whom it may concern:

Be it known that I, ROBERT MIEHLE, a citizen of the United States, and a resident of the city of Chicago, in the county of Cook and State of Illinois, have invented a certain new and useful invention in Devices for Giving Positive Motion to Sliders of Printing-Presses, of which the following is a specification—to wit:

10 This invention relates to that class of printing-presses in which the press-bed is reciprocated in tracks or ways in which are fitted slider-frames with anti-friction rollers for the bed to travel upon. The sliders in working 15 properly should have a reduced movement just one-half of that which is imparted to the bed, and to keep the sliders positively in their proper working position a separate device is necessary.

20 The object of this invention is to provide in connection with the slider-frames a very simple and effective device and construction of parts, by which the slider-frames are positively kept in their proper working position in relation 25 with the movement of the press-bed.

In order to enable others skilled in the art to which my invention appertains to make and use the same, I will now describe its construction and operation, reference being had to the 30 accompanying drawings, in which—

Figure 1 is a longitudinal vertical section of the present invention; Fig. 2, a transverse vertical section of the same. Fig. 3 is a longitudinal vertical section of a modified form 35 of the present invention; Fig. 4, a transverse vertical section of the same, showing one of the belts in section.

A represents a press-frame, which may be of any of the usual constructions; B, a press-bed, 40 which is usually reciprocated horizontally in tracks or ways B', into which are fitted slider-frames c' c'', containing anti-friction rollers c, upon which the bed B rests.

In operation the press-bed B receives a reciprocating movement by any suitable mechanism, which it is thought unnecessary to show. It is evident that the bed B should impart to the slider-frames c' c'' a movement just one-half of that received by the said bed; but in 45 practice the slider-frames have a tendency to alter their proper position in relation to the said bed, and to prevent the same altering their

position there is secured to the under side of the bed B a hanger, g, and thereto is connected a belt, D, which passes around the pulleys f f', 55 the said pulleys being secured to the slider-frame c'. The ends of the belt are then extended to the center of the press, and are connected to the hanger g'', secured to the stationary track or way B'.

The operation of the device just described being such that when the bed B receives a reciprocating movement the belt D will be drawn around the pulleys f in such manner as to impart to the slider-frame c' a reduced 60 movement, just one-half the movement of the bed B at any time the slider-frame has a tendency to alter its proper position in relation to the bed B. The other slider, c'', is kept in its proper position by the cross-bar F, which is 65 connected to both the slider-frames c' c'', so that they will move together, or the slider-frame c'' may be fitted the same as the slider-frame c'. Each slider-frame in that case would 70 act independently of the other.

The present invention may be somewhat modified—for instance, as shown in Figs. 3 and 4, in which a pulley, f', is placed at the center of the slider-frame c', and the belt is divided into two parts, D D', as indicated in Figs. 3 and 4, 80 which are connected to hangers g g' at each end of the bed B, thence passing around the pulley f, and connected to the hangers g'' g'' upon the track or way B'. It will evidently be seen that the operation of this arrangement is similar to the one heretofore described; and, furthermore, one of the belts D D' may be dispensed with, and in such case the belt would be arranged in a manner to pass around but one 85 side of the pulley, its function then being only 90 to limit the movement of the slider-frame in the direction it has a tendency to alter or shift from its proper position.

It is evident that a cord or wire rope, and also a metal band or chain, or any other suitable 95 material having enough flexibility to wind around the pulleys, may be applied, instead of a belt, as herein described. I therefore do not limit myself to the use of a belt.

What I claim as new, and desire to secure by 100 Letters Patent, is—

1. In combination with the slider-frame of a printing-press, a belt connected to the press-bed and press-frame, passing around a pulley

which is connected to the slider-frame to impart a reduced movement to the slider, substantially as described.

2. In combination with the slider-frame of a printing-press, a belt connected to the press-bed and press-frame, passing around pulleys which are connected to the slider-frame to impart a reduced movement to the slider, substantially as described.
- 5 3. In combination with the slider-frame of a printing-press, a belt connected to the press-

bed and press-frame, and passing around pulleys which are connected to the slider-frame and cross-bar F to impart a reduced movement to both sliders, substantially as described.

15 In testimony whereof I have signed my name to this specification in the presence of two subscribing witnesses.

ROBERT MIEHLE.
